SMOKING DEVICE

Walter C. Geseck, Buffalo, N. Y.

Application July 24, 1940, Serial No. 347,184

5 Claims. (Cl. 131—207)

This invention relates to a smoking device such as a smoking pipe or a holder for cigars and cigarettes and has for its objects the provision of simple and efficient means whereby the smoke from the burning tobacco is cooled and condensed and deprived of nicotine bearing moisture juice, or tobacco tar before it reaches the mouth of the smoker and which is so organized that the same can be quickly, conveniently and easily cleaned when an accumulation of moisture makes this desirable in order to render smoking enjoyable to the fullest extent.

In the accompanying drawing:

Fig. 1 is a longitudinal section of a pipe embodying a satisfactory form of the improvements forming the subject of this invention.

Fig. 2 is a top plan view of the head portion of the pipe.

Fig. 3 is a fragmentary horizontal section, taken on line 3—3, Fig. 1.

Figs. 4, 5, 6, and 7 are vertical sections, taken respectively on the correspondingly numbered lines in Fig. 1.

In the following description similar characters of reference indicate like parts in the several figures of the drawings:

The smoking pipe shown in the drawings, as an example of one use of this invention, comprises a head 10 having a bowl receptacle or pocket 11, the upper end of which is open for introducing the tobacco or other material to be smoked, and a stem 12 through which the smoke of the burning tobacco is withdrawn from the bowl.

The lower part of the head contains a baffle chamber 13 in which a partial cooling and condensation of the tobacco smoke is effected. This chamber being formed in a tubular neck 18 projecting downwardly from the underside of the bowl 11 and closed at its top by a partition 15 which forms the bottom of the bowl and normally closed at its lower end by a lower head 17 which may be detachably connected with the neck by a screw joint 171 as shown in Fig. 1, or by any other suitable means. The smoke of the tobacco burning in the bowl or receptacle 11 passes from the latter into the baffle chamber by an inlet 14 arranged in the bottom 15 of this receptacle and the smoke escapes from the baffle chamber through a transfer opening 16 in the front side of the baffle chamber which forms an outlet for the latter and an inlet for the stem. The bottom 17 of the baffle chamber is removably connected with the tubular neck 18 thereof to permit of introducing baffle means into the baffle chamber whereby the smoke is compelled to take a circuitous course from the time it enters the baffle chamber to the time it leaves the same and thus causes the smoke to cool and deposit some of the moisture contained therein.

These baffle means in their preferred form, as shown in Figs. 1, 2 and 3, are constructed as follows:

The numeral 19 represents a cap shaped plug 5 secured in an opening or seat 14 in the bottom of the tobacco bowl and provided with a plurality of smoke passages or openings 20. Into the lower end of this plug is fitted the upper end of an upright intermediate baffle tube 21 the bore 22 10 of which forms a downward continuation of the smoke openings 20 and which has its lower end open and terminating between the bottom 15 of the bowl and the bottom 17 of the baffle chamber. In order to insure escape of smoke from the lower end of the intermediate baffle tube 21 regardless of whether the same contacts with any other part, this end of said tube is provided with a plurality of notches 23 through which smoke can pass laterally from the interior to the exterior 20 of this tube.

Within the intermediate baffle tube 21 is arranged an inner upright baffle tube 24, which is of smaller diameter than the bore of the intermediate baffle tube 21 so as to form the annular passage 22 therebetween which communicates at its upper end with the smoke openings 20. The bore of the inner baffle tube 24 forms a vertical passage 25 and its upper end preferably terminates short of the plug 19 and is provided at its upper end with a head 26 and has its lower end terminating short of the bottom 17 of the baffle chamber and provided with a plurality of notches 27 which permit the passage of smoke from the lower part of the baffle chamber into the lower end of the passage 25 formed by the bore of the inner or central baffle tube 24 regardless of whether the lower end of this tube and the bottom of the baffle chamber are in engagement.

The numeral 28 represents a horizontal baffle disk which projects laterally from the lower part of the intermediate baffle tube 21 and is provided at its peripheral edge with a plurality of notches 29 for the passage of smoke from the underside to the upper side of this disk and the opposing sides of the intermediate tube 21 and an outer tubular baffle wall 30. The latter surrounds the baffle disk 28 and is spaced from the inner side of the tubular neck 18 and is of smaller diameter than the bore of said neck so as to form between them an upright outer annular passage 31 which places the spaces in the upper and lower parts of the baffle chamber 13 in communication with each other. The upper edge of the outer baffle wall 30 is provided with an annular row of notches 32 which tend to divide the smoke into a plurality of small streams as the same passes over this wall and thereby promote cooling of the same.

Within the lower part of the baffle chamber 13

is arranged a lower baffle head 33 which engages at its inner edge with the periphery of the lower part of the inner baffle tube 24 and connected at its outer edge with the lower end of the outer baffle wall 30. This lower baffle head 33 is spaced from the underside of the baffle disk 28 by an intervening passage 34 which places the lower end of the passage 22 in a communication with the space 9 within the tubular baffle wall 30 above the baffle disk 33. This lower baffle head 33 is also spaced from the bottom 17 of the baffle chamber 13 by a passage 35 which places the lower end of the annular passage 31 in communication with the lower end of the passage 25 in the inner baffle tube 24. On the lower part of the periphery of the outer baffle wall 30 an annular row of projections 36 is provided which engages the bore of the neck 18 and form notches for the passage of smoke from the annular passage 31 to the horizontal passage 35.

The smoke is conducted from the upper end of the inner baffle tube 24 into the rear end of the pipe stem 12 by a horizontal conduit including an inner coupling tube section 37 connected at its inner end with the upper part of the inner baffle tube 24 and extending laterally therefrom through the adjacent part of the intermediate baffle tube 21 and an outer coupling tube section 38 which extends through the outlet opening 16 of the baffle chamber and projects with its rear end through the outer baffle wall 30 and into the inner tube section 37 while its front end projects into the rear part of the pipe stem.

During the smoking operation the smoke from the tobacco burning in the bowl of the head passes successively downwardly through the openings 20 and vertical passage 22, thence horizontally outward through the notches 23 and horizontal passage 34, thence upwardly through the notches 29 and passage 9, thence horizontally outward through the notches 32 and the upper end of the baffle chamber 13, thence downwardly through the passage 31, and the notches between the projections 36, thence horizontally inward through the passage 35 and notches 21, thence upwardly through the passage 25 in the inner tube 24, and thence horizontally outward through the coupling tube sections 37, 38 to the rear end of the pipe stem, during which course the stream of smoke takes a circuitous or serpentine path and not only is cooled during this passage but laden nicotine moisture entrained in the smoke is separated therefrom and deposited on the surfaces along which the smoke flows.

The baffle means embodied in the stem of this smoking device and containing this invention are constructed as follows:

In its preferred form the pipe stem comprises a rear tubular section 39 which is detachably connected with the head of the pipe, a front tubular section 40 terminating at its front end in a mouthpiece 41 which is placed in the mouth of the smoker for drawing the smoke forwardly from the bowl through the stem, and an intermediate tubular section 8 which is interposed between said front and rear stem sections.

The rear stem section 39 is provided at its rear end with a tubular socket 18 in which the neck 18 of the pipe head is seated, this socket being open at its upper end while its lower end may be closed by a bottom 35 or left open. The stem sections have their bores enlarged, as shown at 42, 6, 43 in Fig. 1 thereby forming a forwardly facing internal shoulder 44 on the rear stem section 42 and a rearwardly facing internal shoulder 75

45 on the front stem section 40 while the intermediate section has a bore 6 of the same diameter as that of the rear stem section and is not provided with any internal shoulders. Within 5 the bores of the stem sections are arranged the rear section 46 and the front section 47 of a tubular lining, said rear lining section being of comparatively large diameter and extending the full length of the bore 42 of the rear stem section 10 and the bore 6 of intermediate section and provided at its rear end with a circular head or collar 48 which bears against the shoulder 44. At its rear end the rear pipe stem section 39 is provided with an opening 161 which registers 15 with the opening 16 in neck 181 and through which the front tube section 38 projects forwardly into the smoke space 49 formed in the bore of the rear lining section 46. The front lining section is of smaller diameter than the rear lining section 46 and bears at its front end 20 against the shoulder 45 of the front stem section while its rear end projects rearwardly beyond the rear end of the front stem section and intermediate stem section and telescopes into the front 25 end of the rear lining section 46 to form a slip joint connection therewith. The rear lining section 46 is preferably secured to the intermediate stem section 8 by a rivet 7, or otherwise, and is 30 slidably into and out of the bore of the rear stem section 39. The head 48, the smoke inlet tube 38 and the rear lining section 46 are preferably connected so that they may be moved as a unit.

In their preferred form the baffle means associated with the stem of the pipe are constructed as follows:

The numeral 58 represents a front smoke outlet tube arranged axially within the front and intermediate parts 40, 8, of the stem and having its rear end spaced from the front end of said smoke inlet tube 38 while its front end is fitted 40 in a socket 51 in the front section of the pipe stem and communicates with a smoke duct 52 extending to the front end of the mouthpiece 41.

The numeral 53 represents a baffle tube arranged lengthwise within the tubular lining sections 46, 47 and having its front part surrounding the rear part of the front smoke outlet tube 58 while its rear end is arranged opposite the front end of the smoke inlet tube 38. The front 45 part of the baffle tube 53 has a diameter smaller than that of the adjacent front section 41 of the tubular lining and greater than that of the smoke outlet tube 58 and its front end terminates short of the shoulder 45 on the front stem section, thereby forming an annular outer longitudinal smoke passage 54 between the outer side of this baffle tube 53 and the front lining section 43 which communicates at its rear end by means of the smoke space 49 with the front end of the smoke inlet tube 38, and at its front end with the front end of a longitudinal inner smoke passage 55 arranged between the tubes 58, 53. The passage 55 communicates at its rear end with the rear end of the smoke outlet tube 58, as shown in Fig. 1. The baffle tube 53 is held in a central position relative to the smoke outlet tube 58 by an annular row of projections or corrugations 56 arranged on the exterior of the smoke outlet tube 58 and bearing against the bore of this baffle tube 53 and the latter is held in a central position relative to the front tubular lining section 47 by annular rows of projections or corrugations 57, 58 arranged on the exterior of the front and rear parts of this baffle tube and engaging with the adjacent parts of the front lining section 47.

The rear end of the baffle tube 53 is preferably tapered rearwardly and a plug 59 of absorbent material, such as cotton, is placed in this tapered portion so that it forms an absorbent wall between the front end of the smoke inlet tube 38 and the rear end of the smoke outlet pipe 50 which absorbent wall is however spaced from the front end of the tube 38. Retention of the absorbent plug in the tapering part of the baffle tube 53 is effected by providing this tapering part with one or more openings 60 into which parts of the plug project and thereby become interlocked therewith so as to prevent these parts from becoming separated too freely.

In the operation of the baffle means in the pipe stem the smoke issuing from the front end of the inlet tube 38 first strikes the rear end of the absorbent plug 59 and deposits nicotine laden moisture thereon. The latter absorbs this moisture and deflects the smoke laterally into the space 49 within the rear part of the rear lining section 46. From thence the smoke passes forwardly through the outer longitudinal passage 54, thence rearwardly through the inner longitudinal passage 55 and against the front side of the plug 59 so that further moisture in the smoke is deposited on this plug. Thereafter the smoke passes forwardly through the smoke outlet tube 50 and passage 52 in the mouthpiece to the mouth of the smoker. During the circuitous course of the smoke through the stem of the pipe the smoke is cooled and moisture is removed from the smoke.

For the purpose of cleaning the pipe the head and stem may be separated and a considerable part of the moisture in the head can be removed by sharply whipping the same after the bottom 17 has been removed. Likewise a substantial amount of the moisture in the stem can be removed therefrom through the tube 38 by whipping the stem while it is held in the hand by the mouthpiece. If thorough cleaning of the pipe is desired the members of head and stem may be completely disassembled so that all of the several parts are fully accessible.

In the operation of the pipe virtually all of the moisture produced by the cooling of the smoke in the stem is collected in the chamber 49 which forms a catching cup and also absorbed by the plug 59 so that little, if any, reaches the mouth of the smoker. When the plug becomes saturated the same can be readily replaced by a new one, and excess moisture in the chamber 49 can also be easily removed as often as required by blowing backwardly through the stem.

The baffle means in the pipe are all of simple construction, the same can be readily manufactured at low cost and easily assembled and the same can also be easily disassembled for inspection, cleaning, repairing and replacing any parts.

I claim as my invention:

1. A smoking device comprising a tubular stem having an inlet and an outlet, a smoke inlet tube arranged in said inlet, a smoke outlet tube arranged in said outlet, said inlet and outlet tubes being arranged axially in line but having their opposing ends spaced apart within said stem, an intermediate baffle tube of larger diameter than said inlet and outlet tubes arranged within said stem and having its rear end opposite said inlet tube and its front end surrounding said out-

let tube, and an absorbent plug arranged in said intermediate tube between said inlet and outlet tubes but spaced from the same.

2. A smoking device comprising a tubular stem having an inlet and an outlet, a smoke inlet tube arranged in said inlet, a smoke outlet tube arranged in said outlet, said inlet and outlet tubes being arranged axially in line but having their opposing ends spaced apart within said stem, an intermediate baffle tube of larger diameter than said inlet and outlet tubes arranged within said stem and having its rear end opposite said inlet tube and its front end surrounding said outlet tube, and an absorbent plug arranged in said intermediate tube between said inlet and outlet tubes but spaced from the same, the rear end of said intermediate tube being tapered rearwardly and provided with perforations.

3. A smoking device comprising a tubular stem having an inlet and an outlet, a smoke inlet tube arranged in said inlet, a smoke outlet tube arranged in said outlet, said inlet and outlet tubes being arranged axially in line but having their opposing ends spaced apart within said stem, an intermediate baffle tube of larger diameter than said inlet and outlet tubes arranged within said stem and having its rear end opposite said inlet tube and its front end surrounding said outlet tube, and an absorbent plug arranged in said intermediate tube between said inlet and outlet tubes but spaced from the same, the rear end of said outlet tube being provided externally with an annular row of projections which engage with the bore of the adjacent part of said intermediate tube to form a plurality of smoke passages between said baffle tube and outlet tube.

4. A smoking device comprising a tubular stem having an inlet and an outlet, a smoke inlet tube arranged in said inlet, a smoke outlet tube arranged in said outlet, said inlet and outlet tubes being arranged axially in line but having their opposing ends spaced apart within said stem, an intermediate baffle tube of larger diameter than said inlet and outlet tubes arranged within said stem and having its rear end opposite said inlet tube and its front end surrounding said outlet tube, an absorbent plug arranged in said intermediate tube between said inlet and outlet tubes but spaced from the same, and a lining tube surrounding said baffle tube but spaced therefrom and engaging the bore of said stem, said baffle tube being provided externally with an annular row of projections which engage with the bore of said lining tube and produce a plurality of smoke passages between said baffle tube and said lining tube.

5. A smoking device comprising a tubular stem having rear and front sections provided respectively with a smoke inlet and a smoke outlet, a tubular lining having telescopic rear and front sections engaging with the bore of said rear and front stem sections, a rear inlet tube arranged in said rear smoke inlet, a front outlet tube arranged in said front smoke outlet and spaced from said rear inlet tube, an intermediate baffle tube arranged within said lining tube and surrounding said front outlet tube, and an absorbent plug arranged in said baffle tube and spaced from the opposing ends of said rear inlet and front outlet tubes.
